UNITED STATES PATENT OFFICE.

CHARLES DE NOVO, OF OAK PARK, ILLINOIS.

STEAM BOILER.

Application filed April 2, 1926. Serial No. 99,201.

The invention relates to steam boilers.

In the use of steam boilers, the joints between the flues and the flue-sheet or boiler head often become loose due to the differential contraction and expansion of the flues and sheet caused by the temperature variations in the water chamber and combustion chamber, and leakage of the water into the combustion chamber results. The primary object of the present invention is to provide means for effectively preventing the flue joints of boilers from becoming loose. In general, this means comprises a wall of fire-brick which is disposed adjacent and contacts directly with the flue-sheet and operates to maintain the joints at a substantially uniform temperature regardless of the sharp variations in the temperature in the water and combustion chambers.

The invention consists in the several novel features hereinafter set forth and more particularly defined by the claims at the conclusion hereof.

In the drawings: Fig. 1 is a rear view of a boiler showing the new and improved brick-work applied to a portion of the flue-sheet. Figs. 2 and 3 are detail perspectives of a brick which is used in the construction of the brick-work. Fig. 4 is a section taken on the line 4—4 of Fig. 1. Fig. 5 is an enlarged section of the flue joints.

The invention is exemplified in an internally heated boiler comprising a cylindrical wall or body 5 which forms the outer shell and water chamber of the boiler; an annular flue-sheet or head 6 which is riveted or secured in any other suitable manner to one end of the wall 5 and forms the rear end of the boiler; a furnace 7 which is formed of a transversely corrugated pipe and has one end secured to the flue-sheet 6; a combustion chamber 9; and flues 10 which extend forwardly from the flue-sheet and are adapted to convey the products of combustion from the combustion chamber 9 and discharge them into a stack (not shown) as well understood in the art. The combustion chamber is formed by the flue-sheet 6, a base wall 11, a rear wall 12, side walls 13, and a top wall 14. The latter is composed of members 15 which have their rear ends secured to the rear wall 12 and their front ends secured to an angle bar 17 which extends horizontally across the flue-sheet and is rigidly secured thereto. Members 15 are arched and are adapted to direct the

products of combustion toward the flues. Walls 11, 12, 13 and 14 are formed of fire-brick and may be of any suitable construction. An opening 19 is formed in the rear wall 12 to permit access to the combustion chamber 9 so that work may be done upon the flues 10 and the furnace 7.

Flues 10 extend through openings 6^a in the flue-sheet 6 and are beaded over as at 10^a so as to form fluid-tight joints between the flues and the flue-sheet. To prevent these joints from becoming loose, due to the contraction and expansion of the flues, a wall 20 of fire-brick is formed against the rear surface of the flue-sheet 6. This wall is adapted to retain its heat and thus maintain the flue-sheet 6 and the flue joints at a substantially uniform temperature regardless of the sharp variations in the temperature in the combustion chamber 9 and the water chamber. Wall 20 is composed of a course of solid arc-shaped bricks 21 which extend around the opening in the flue-sheet for the furnace 7; a course of solid bricks 23 which extend between bricks 21 and the side walls 13 of the combustion chamber, and terminate below the flue openings 6^a; and a course of bricks 24 which extend upwardly from bricks 23 and terminate adjacent the angle bar 17 and the top wall 14 of the combustion chamber. A pair of cylindrical openings 24^a are formed in each brick 24 and extend transversely therethrough. These openings in bricks 24 are adapted to communicate with the flues so as to permit the products of combustion to escape from the combustion chamber to the flues. The inner surface of each brick 24 is provided with an annular groove 24^b adjacent each opening 24^a. These grooves form sockets into which the beaded ends of the flues are secured. Wall 20 is contiguous to the flue-sheet and is formed of a single thickness of bricks.

The invention exemplifies a steam boiler in which a brick-work is formed against the flue-sheet which will maintain the flue-sheet and joints at a substantially uniform temperature, and thus prevent the joints from becoming loose due to differential expansion and contraction, resulting from variations in temperature in the combustion chamber and water chamber.

The invention is not to be understood as restricted to the details set forth, since these may be modified within the scope of the

appended claims, without departing from the spirit and scope of the invention.

Having thus described the invention, what I claim as new and desire to secure by Letters Patent, is:

1. In a boiler, the combination of an outer shell, a flue sheet, a combustion chamber adjacent one side of said sheet, flues extending through the sheet and leading from the chamber, and a wall of fire-brick disposed within the combustion chamber and completely covering that part of the said one side of the sheet which is contiguous thereto, said wall contacting directly with the flue connections and said part of the sheet and operating to maintain the connections and sheet at the same and a substantially uniform temperature, the bricks of said wall adjacent the flues being provided with holes extending therethrough and in communication with the flues.
2. In a boiler, the combination of an outer

shell, a flue sheet, a combustion chamber adjacent one side of said sheet, flues extending through the sheet and leading from the chamber, said flues being beaded over at said one side of the sheet to form fluid-tight joints between them and the sheet, and a wall of fire-brick disposed within the combustion chamber and completely covering that part of the said one side of the sheet which is contiguous thereto, said wall contacting directly with said part of the sheet and the beaded ends of the flues and operating to maintain the joints and sheet at the same and a substantially uniform temperature, the bricks of said wall adjacent the joints being provided with holes extending therethrough and in communication with the flues, and sockets for receiving the beaded ends.

Signed at Chicago, Illinois, this 19 day of March, 1926.

CHARLES DE NOVO.
